UNITED STATES PATENT OFFICE.

WALTER A. CROWDUS, OF CHICAGO, ILLINOIS.

BRAKE.

SPECIFICATION forming part of Letters Patent No. 703,553, dated July 1, 1902.

Application filed September 16, 1901. Serial No. 75,466. (No model.)

To all whom it may concern:

Be it known that I, WALTER A. CROWDUS, a citizen of the United States, and a resident of Chicago, in the county of Cook and State 5 of Illinois, have invented an Improved Brake, of which the following is a specification.

This invention relates to brakes, and relates particularly to band-brakes.

A primary object of the invention is to provide a brake by means of which the shaft or axle to which it is applied may be effectively "braked" when rotating in either direction.

A brake of my invention is particularly designed and adapted for use on motor-vehicles, 15 but is equally adapted for use on any shaft which rotates in both directions.

The invention consists of the various features, combinations of features, and details of construction hereinafter described and 20 claimed.

In the accompanying drawings a brake of my invention is fully illustrated.

Figure 1 is a side view of a brake of my invention, partly in section, showing the brake 25 released. Fig. 2 is an end view thereof. Fig. 3 is a partial plan section on the line 3 3 of Fig. 4, and Fig. 4 is a view showing the relation and position of parts for braking the shaft or axle when rotating in the direction 30 indicated by the arrow.

Referring now to the drawings, 1 designates a revoluble shaft, as the axle of a motor-vehicle, 2 a brake-drum secured to said shaft, and 3 a brake-band applied to said 35 brake-drum. All of the foregoing elements are old in the art and may be of any usual or approved construction.

The ends of the strap 4 of the brake-band 3 are anchored to a rigid support by means of 40 a connection therewith adapted to permit movement of said brake-band in either direction to apply the brake. In the specific construction shown metal plates 5 are secured to the ends of said brake-band outward lugs or 45 projections 6, on which are adapted to engage and normally rest against shoulders or ledges 7 on a bracket 8, secured to a rigid support 9 adjacent to the brake-drum 2, the length of the brake-band being such that when said 50 lugs or projections 6 are both in contact with

their respective stops the brake will be released. Preferably, also, the metal strap is made of elastic or spring metal bent to a larger diameter than the diameter of the drum. Thus when the brake is released the 55 elasticity of the strap 4 will disengage the brake-band 3 from the brake-drum 2 and will prevent said brake-band from adhering to the brake-drum, which would increase the resistance to the rotation of the shaft. As shown, 60 also, the bracket 8 comprises two webs, which extend down one on each side of the brake-band and closely adjacent thereto. Said webs thus form guides adapted to retain the brake-band in operative position upon the 65 brake-drum.

The ends of the brake-band 3 are adapted to be depressed into frictional engagement with the brake-drum 2 by a shoe 10, supported so as to be movable toward and from 70 the brake-drum, which overlaps the ends of the brake-band 3 and has mounted in its ends rollers 11, adapted to bear upon the plates 5, secured to the ends of said brake-band. As shown, the shoe 10 is adapted to be depressed 75 into desired frictional engagement with the plates 5 by means of an eccentric 12, mounted in the webs of the bracket 8. Preferably, also, a strap 13, secured to said shoe, passes over said eccentric 12, whereby said shoe may be 80 raised out of contact with the plates 5 when it is desired to release the brake.

As shown, rotation is adapted to be imparted to the eccentric 12 by means of a lever 14, secured to the projecting end of the pivot-pin 15 of said eccentric 12, said lever being connected to a hand or foot lever (not shown) by means of a rod 16.

The operation of my improved brake is as follows: It being desired to apply the brake, 90 the eccentric 12 is thrown, by means of its described connections, so as to depress the shoe, and thus force the ends of the brake-band into frictional engagement with the brake-drum. Such frictional engagement of said 95 brake-band with the rotating brake-drum will tend to impart movement to said brake-band circumferentially of said brake-drum in the direction of rotation thereof. The rollers 11, which bear upon what may be 100

called the "front" end of the brake-band when referred to the direction of rotation of the brake-drum, will permit movement of said brake-band with said drum until said brake-band is drawn tightly down upon said drum, after which further movement of said brake-band will be prevented by the stops which connect the rear end of said brake-band to the support or bracket 8. Additional pressure on said shoe 10 will only draw the brake-band into tighter and more efficient engagement with the brake-drum.

Practical tests have demonstrated that my improved brake is very efficient. So powerful is it, in fact, that there is danger of "skidding" the wheels in setting the brake. To obviate this, I prefer to make the rod 16 in sections connected by a compression-spring, (not shown,) whereby the brake will always be set with substantially uniform power.

I claim—

1. A band - brake comprising a drum, a brake-band applied thereto, means relatively to which said brake-band is movable to force the ends of said brake-band into frictional engagement with said brake-drum and stops which limit the movement of said brake-band circumferentially of said drum, substantially as described.
2. The combination with a revolute shaft, of a drum secured thereto, a brake-band applied to said drum, a support adjacent to said drum to which the ends of the brake-band are anchored by means of a movable connection, a shoe supported so as to be movable toward and from the brake-drum which overlaps the ends of the brake-band and means to impart movement to said shoe toward said brake-drum, substantially as described.
3. The combination with a revolute shaft, of a drum secured thereto, a brake-band applied to said drum, a support adjacent to said drum to which the ends of the brake-band are anchored by means of a movable connection, a shoe supported so as to be movable toward and from the brake-drum, rollers mounted therein adapted to bear upon the ends of the brake-band and means to impart movement to said shoe toward the brake-drum, substantially as described.
4. The combination with a revolute shaft, of a drum secured thereto, a brake-band applied to said drum, plates secured to the ends of said brake-band, a support adjacent to said drum to which the ends of the brake-band are anchored by means of a movable connection, a shoe supported so as to be movable toward and from the brake-drum, rollers mounted in said shoe adapted to bear upon the plates secured to the brake-band and means to impart movement to said shoe toward the brake-drum, substantially as described.
5. The combination with a revolute shaft, of a brake-drum secured thereto, a brake-band

applied to said drum, a support to which the ends of the brake-band are anchored by means of a movable connection, a shoe supported therein so as to be movable toward and from the brake-drum, rollers mounted in said shoe and adapted to bear upon the ends of the brake-band and means to impart movement to said shoe toward the brake-drum, substantially as described. 70

6. The combination with a revolute shaft, of a drum secured thereto, a brake-band applied to said drum, a support to which the ends of the brake-band are anchored by means of a movable connection, said support comprising webs or flanges which closely embrace the sides of the band, a shoe supported therein so as to be movable toward and from the brake-drum, rollers mounted in said shoe adapted to bear upon the ends of said brake-band and means to impart movement to said shoe toward said brake-drum, substantially as described. 80

7. The combination with a revolute shaft, of a drum secured thereto, a brake-band applied to said drum, a support, stops thereon adapted to limit the movement of said brake-band, a shoe, rollers therein adapted to bear upon the ends of said brake-band, an eccentric mounted in said support and adapted to depress said shoe and means to throw said 90 eccentric, substantially as described.

8. The combination with a revolute shaft, of a drum secured thereto, a brake-band applied to said drum, a support, plates secured to said brake-band, stops on said plates adapted to engage rigid portions of said support, a shoe, rollers therein adapted to bear upon the plates on said brake-band, an eccentric mounted in said support adapted to depress said shoe and means to throw said eccentric, 100 substantially as described.

9. The combination with a revolute shaft, of a drum secured thereto, a brake-band applied to said brake-drum, a support, shoulders or ledges thereon, plates secured to said brake-band, projections on said plates adapted to engage the shoulders or ledges on said plates, a shoe, rollers therein adapted to bear upon the plates on said brake-band, an eccentric mounted in said support adapted to depress said shoe, a strap on said shoe which passes over said eccentric and means to throw said eccentric, substantially as described. 110

10. A band - brake comprising a drum, a brake-band applied thereto, rollers revolvably mounted above the ends of said brake-band so as to be movable toward and from the brake-drum, means to depress said rollers upon the ends of said brake-band, and stops which limit the movement of said brake-band circumferentially of said drum, substantially as described. 120

11. A band - brake comprising a drum, a brake-band applied thereto, plates secured to the ends of said brake-band, rollers revolvably 130

mounted above said plates so as to be movable toward and from the brake-drum, means to depress said rollers upon the plates on said brake-band and stops adapted to limit the movement of said brake-band circumferentially of said drum, substantially as described.

5 In testimony that I claim the foregoing as

my invention I affix my signature, in presence of two subscribing witnesses, this 23d day of August, A. D. 1901.

WALTER A. CROWDUS.
